US00D769289S

(12) **United States Design Patent** (10) **Patent No.:** **US D769,289 S**
Cho et al. (45) **Date of Patent:** **** Oct. 18, 2016**

(54) **DISPLAY SCREEN OR PORTION THEREOF
WITH GRAPHICAL USER INTERFACE**

(71) Applicant: **Samsung Electronics Co., Ltd.**, Suwon-si, Gyeonggi-do (KR)

(72) Inventors: **Eun nim Cho**, Yongin-si (KR); **Jiny Kwon**, Seongnam-si (KR)

(73) Assignee: **SAMSUNG ELECTRONICS CO., LTD.**, Suwon-Si, Gyeonggi-Do (KR)

(**) Term: **15 Years**

(21) Appl. No.: **29/530,682**

(22) Filed: **Jun. 18, 2015**

(30) **Foreign Application Priority Data**

Dec. 31, 2014 (KR) 30-2014-0064540

(51) **LOC (10) Cl.** **14-04**

(52) **U.S. Cl.**

USPC **D14/486**

CLAIM

We claim the ornamental design for a display screen or portion thereof with graphical user interface, as shown and described.

DESCRIPTION

FIGURE is the front view for a display screen or portion thereof with graphical user interface showing our new design.

The broken lines in the drawing show unclaimed environment only and form no part of the claimed design.

The dot dash lines in the figures represent an unclaimed boundary line and form no part of the claimed design.

1 Claim, 1 Drawing Sheet
